DISPLAY DEVICE

Ralph J. Mancuso, Brooklyn, N. Y., assignor to
 Royal Mounters, Inc., Long Island City, N. Y., a
 corporation of New York

Application September 29, 1937, Serial No. 166,282

11 Claims. (Cl. 40—155)

The present invention relates generally to improvements in display devices of the collapsible picture frame type, wherein a body portion or center panel of the device, adapted to receive and display suitable advertising matter, is surrounded by a raised border or margin simulating a picture frame.

It has been found that such displays with their three dimensional appearance attract the attention of a greater number of persons than where merely a flat type of display is used. Also, the appearance of a photograph or the like placed on the body portion of the device is considerably enhanced.

16 The invention is directed more particularly to an improved construction for connecting the corners of the device to facilitate erection to display position and collapsing quickly to a single plane for shipping and storing.

20 Picture frame types of display devices have heretofore been generally known but they have not proven as satisfactory and as practical as desired. One of the chief difficulties with prior types has been in obtaining an efficient means 25 and method for holding the device in display position, that is, means to hold the frame surrounding the body portion in raised and outwardly extending relation thereto.

25 Heretofore, such frames have had to be cut and folded, secured with adhesive, tacks, clips, etc., or else the frame was provided with externally visible slots on one part into which cooperating tongues or hook-shaped portions on the other part have had to be fitted. These prior types 35 were difficult to assemble and could not be quickly and easily collapsed. The hook-shaped portions were easily broken off or the slots were enlarged or torn open by frequent assembly and disassembly of the device. In addition, such hooks 40 and slots were unsightly and marred the appearance of otherwise pleasing picture frame displays. The disadvantages of using adhesives, tacks, clips, etc. to secure the prior devices are many.

The present invention aims to provide a simple, 45 inexpensive and thoroughly practical means for securing and retaining a picture frame device in display position. The present invention also contemplates the provision of means for quickly and easily assembling or collapsing a picture frame 50 display card without the necessity of first interfitting or releasing and securing members. The invention further contemplates the provision of a picture frame display card which is attractive in appearance and does not require the assembling 55 of interlocking projections or the use of

tacks, staples, clips or the like to retain the parts in display position.

An object of the present invention is to provide an inexpensive and more practical picture frame display. 5

Another object of the invention is to provide a picture frame display device adapted to be easily and quickly assembled or collapsed.

Another object of the invention is to provide a picture frame display device which may be set up 10 or disassembled with minimum effort and skill on the part of the user.

Another object of the invention is to provide a picture frame display device of improved appearance which may be quickly and easily col- 15 lapsed to occupy a minimum amount of space.

Other and further objects of the invention will be obvious upon an understanding of the illustrative embodiment about to be described or will be indicated in the appended claims and various ad- 20 vantages not referred to herein will occur to one skilled in the art upon employment of the invention in practice.

A preferred embodiment of the invention has been chosen for purposes of illustration and de- 25 scription and is shown in the accompanying drawing, forming a part of the specification, wherein

Fig. 1 is a perspective view showing a preferred embodiment of the present invention; 30

Fig. 2 is a rear elevational view of the present invention in collapsed position;

Fig. 3 is an enlarged fragmentary view of one corner of the present invention in collapsed position; 35

Fig. 4 is an enlarged fragmentary view of the corner illustrated in Fig. 3 in display position; and

Fig. 5 is an enlarged fragmentary perspective view of the corner illustrated in Figs. 3 and 4. 40

Referring again to the drawing, and more particularly to Figs. 1 and 2, there is shown a display device of the picture frame type preferably formed from a single sheet of cardboard or other suitable material comprising a body or center 45 portion 1 adapted to receive suitable printing, lithographing, photographing or the like, portions 2 attached to and extending outwardly from the center portion and frame or margin portions 3 attached to and extending outwardly from the 50 portions 2. The outwardly extending portions forming the frame or margin are preferably decorated with appropriate designs in keeping with the display or are made to simulate various kinds of woods. 55

In order to facilitate folding to display position, the single sheet of material, from which the body and outwardly extending portions are preferably formed, is provided with score lines or creases 4 and 5. The inner score line 4 is preferably at the rear of the card to permit the inner frame portion 2 to be folded forwardly and the outer score line 5 is preferably at the front of the card to permit the outer frame portion 3 to be folded rearwardly.

In order to facilitate erection of the device to display position, notches or recesses 9 are preferably cut out of the sheet of material comprising the device at the corners thereof. The outwardly extending portions adjacent to the body or center portion may then be folded to form the raised portions 2 having the outwardly extending frame or margin portions 3 attached thereto.

While the portions 2 have been shown as extending outwardly at an angle to the body portion 1 and the portions 3 as being substantially parallel to the body portion 1, the angles which these parts make with the body portion may be varied to suit the taste of the individual.

When the device is in display position, the ends of adjacent frame portions meet along evenly abutting edges to form a smooth and almost invisible joint.

To retain the frame portions in display position, a new and improved means has been provided (Figs. 2, 3, 4 and 5). For the purposes of illustration and description, there are shown in Figs. 3, 4 and 5 enlarged fragmentary views of the lower right hand corner of the device, as shown in Fig. 2. Fig. 3 shows the construction in collapsed position, Fig. 4 shows the device in display position, and Fig. 5 shows the device in display position with the cover portion 18 of one of the securing members lifted upwardly. These figures bring out in detail the primary improvement constituting the basis of the present application. Similar constructions are used on each corner of the device and a description of one will suffice for all.

Attached at one end thereof to a frame portion 3 by means of adhesive or other suitable means is a member 13, the general configuration of which is shown as substantially a right angle. The free end 20 of this member extends outwardly 50 along the side of an adjacent frame portion 3, substantially at right angles to the attached end of the member and is provided with a notch or recess 14 adjacent to the free end thereof. Secured to the latter frame portion 3 and preferably enclosing at least part of the free end of the first member 13 is a recessed or hollowed-out member 16 provided with a cover 18 and having a projection 17 near one end thereof.

When the picture frame is in collapsed position, the free end 20 of the angle member 13 lies adjacent to the inner side 19 of the recessed member with the notch 14 in proximity to the projection 17 but spaced slightly therefrom. In order to assemble or erect the device, adjacent frame members are pushed toward each other to the position shown in Figs. 4 and 5 so that the outer side of the free leg of the angle member 13 lies adjacent to the side 21 of the recessed member 16. In this position, the free end 20 of the right angle member 13 passes beyond the projection 17 on the recessed member 16 and the projection 17 on the recessed member fits into the recess or notch 14 on the member 13 to secure the parts together so that they will not become detached upon releasing the pressure by means of

which they were assembled. The free end of the right angle member 13 is never completely out of the hollowed-out member 16 but is always partially within the hollow member so that in order to assemble the device to display position one merely has to press adjacent frame portions toward each other. No preliminary interfitting of tongues and slots is necessary.

The free end 20 of the angle member 13 is further adapted to be held in locked relation by the side 22 of the recessed member which acts as a stop to prevent the free end 20 from accidentally loosening from its interlocking relation with the projection 17 and backing out of the recess. The free end 20 of the angle member is preferably retained within the hollow member 16 by means of any suitable overlying portion on the member 16, herein shown as a cover portion 18. The resiliency of the cardboard or other material comprising the angle member 13 is generally such that the free end 20 may readily be snapped over the projection 17 on the recessed member 16. Very little resiliency is needed in the free end of the angle member and the resiliency of the cardboard or other similar material from which this member is preferably formed is sufficient to allow the free end to be sprung into and out of locked relation innumerable times without impairing the effectiveness of the locking means in any way. To further improve the locking means, the hollowed out member 16 is preferably made of thinner material than the angle member so that the free end of the angle member extends slightly above the hollowed member. Thus, when the cover portion 18 (Fig. 4) is in operative position, it will frictionally grip the free end 20 which extends above the hollow member 16 and prevent accidental movement of the locking members and collapsing of the device.

Preferably, the angle members 13 do not all face in the same direction. By having some of the members face in one direction and some in an opposite direction, as shown, for example, in Fig. 2, the forces tending to hold the display device in assembled position are along different lines and, hence, the device will not assume its collapsed form under accidental shocks or jars. The exact facing of the members as shown in Fig. 2 need not be adopted but varying positions may be utilized without departing from the spirit and scope of this feature.

The members 13 and 16, comprising the locking means, cooperate to provide a locking means which is concealed from view, not easily put out of order, and which is adapted to permit easily and quickly setting up or collapsing the device. The free end of the angle member 13 is always in starting position ready to be pushed "home".

In Fig. 2, there is shown a supporting bracket 23 having locking means 25 thereon secured to the rear of the display and adapted to support the display on a flat surface such as a table. If desired, the device may be suspended from a wall or the like by supporting means 26, also at the rear of the device, and having a string or wire attached thereto.

While the present invention has been shown as substantially rectangular in form, it will be understood that other shapes or forms may be utilized without departing from the spirit or scope of the invention. Also, while the body and frame portions have been described as being formed and are preferably formed of a single sheet of material, it is to be understood that the invention is not limited to a one-piece body and frame.

It will be seen that the present invention provides an inexpensive display of the picture frame type which may be readily and easily erected to display position or collapsed without the need of any particular skill on the part of the user. The interlocking parts are in position at all times to be interlocked merely by pressure applied to the sides of the frame. There are no parts which must be interfitted, glued, clipped or otherwise secured together every time the device is assembled or disassembled. There are no loose or exposed parts which may become detached or lost. The device may be quickly assembled or collapsed and has no externally visible locking means to mar its appearance. In addition, the device is rugged in construction and fully capable of withstanding any rough use to which it may be subjected.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. A display device of the picture frame type having outwardly extending marginal portions lying in the plane of the center part of the device when in collapsed position and movable into a plane substantially parallel to the plane of the center part for display position, and means for retaining said marginal portions in display position comprising an L-shaped member attached at one end thereof to one marginal portion with the free end thereof extending over an adjacent marginal portion and a member attached to said adjacent marginal portion having a recess adapted to receive and retain the free end of said L-shaped member, said second member being further provided with a cover portion at least partially overlying the free end of said L-shaped member.

2. A display device having adjacent display sections movable into and out of display position, means connecting adjacent sections adapted to retain them in display position and adapted to readily permit movement thereof into and out of display position, said means comprising a substantially L-shaped member attached at one leg thereof to a display section with the free leg thereof extending over an adjacent display section and a flat member having a recess and a cover portion adapted to receive and retain the free leg of said first member attached to said adjacent display section, said flat member being thinner than the free leg of said L-shaped member whereby the cover portion on said adjacent display section contacts the free leg of said first member.

3. A display device having adjacent display sections movable into and out of display position, said adjacent sections being provided with means adapted to retain them in display position and adapted to readily permit movement thereof into and out of display position, the said means comprising a substantially L-shaped member with one leg thereof attached to a display section with the free end thereof extending over an adjacent display section, and a second member attached to said adjacent section having a recess adapted to receive and retain the free end of said L-shaped member, and a member overlying at least part of said recess and the free leg of said L-shaped member.

4. A display device having adjacent display sections movable into and out of display position, said display sections being provided with means adapted to retain them in display position and to readily permit movement thereof into and out of display position, the said means comprising a member attached at one end thereof to one display section with the free end thereof provided with a recess and extending along an adjacent display section and a flat member attached to said adjacent display section having a recess with a projection therein adapted to receive and retain the free end of said first member.

5. A display device of the picture frame type having adjacent sections movable into and out of display position, a member attached at one end thereof to one display section with the free end thereof extending along an adjacent display section and a flat member attached to an adjacent display section having a recess adapted to receive and retain the free end of said first member, said flat member being of lesser thickness than said first member, and a cover member extending over at least a part of said recess and frictionally engaging the free end of said first member.

6. A display device having adjacent frame sections movable into and out of display position, a member attached at one end thereof to one frame section with the free end thereof extending outwardly over an adjacent frame section and a member attached to said adjacent frame section having a hollowed-out portion adapted to receive the free end of said first member, one of said members having a projection adapted to cooperate with a recess in the other member for maintaining said device in display position and a cover member extending over said first member to assist in retaining the free end thereof within the hollowed-out portion of said second member.

7. A display card comprising a center portion with surrounding marginal frame portions separable from each other and connected adjacent the ends thereof by interlocking means at the rear of said frame portions, said interlocking means being concealed from a person viewing the front and lying against the rear of said frame portions in a plane substantially parallel to the plane thereof, said interlocking means having a member attached at one end thereof to one portion of the display card with its free end lying adjacent a cooperating portion of the display card, and a member with a recess attached to the cooperating portion adapted to retain said free end portion therein, said frame portions lying out of the plane of the center portion when the display card is in display position.

8. A display device of the collapsible picture frame type comprising a display part, frame portions integral with said display part and at the sides thereof, said frame portions being adapted to be collapsed when not in use and adapted to be retained in display position when in use, and concealed means at the rear of said frame portions for retaining said portions in display position comprising a recessed member on one frame portion and a tongue member on another of said frame portions adapted to interengage to retain the frame portions in display position, said tongue member being at least partially within said recessed member when the display device is in assembled or collapsed position.

9. A polygonal shaped display device of the picture frame type formed of cardboard and

comprising a center part having portions at the sides thereof adapted to cooperate in providing a frame for said center part, said frame portions being provided with means adapted to cooperate to secure the ends of adjacent frame portions in adjoining relationship when the display device is in display position, said means comprising a recessed member on one frame portion having a cover member, and an outwardly extending portion on an adjacent frame portion fitting at least partially within said recessed member at all times.

10. A display device having marginal portions movable into display and collapsed position and vice versa, a member attached to one marginal portion of the display device with the free end thereof extending over an adjacent marginal portion and having a recess in said free end, and a second member attached to said adjacent marginal portion of the display device and having a recess adapted to receive said first member and

having a projection in said recess adapted to cooperate with the recess of said first member to hold said first member in position in said recess and to hold said display device in display position.

11. A display device having marginal sections movable into display and collapsed positions, members at the junctions of the respective sections, each member being attached at an end to one section and with its opposite free end extending over an adjacent section, and recess members adapted to cooperate with said first mentioned members, each of said recessed members being secured to one of the sections at the junction thereof and having a recess therein to receive and retain the free end of an adjoining first member to hold said device in display position, and means extending over at least a portion of each recess for limiting lateral movement of said free ends in said recesses.

RALPH J. MANCUSO.
